UNITED STATES PATENT OFFICE.

CHARLES B. STILWELL, OF PHILADELPHIA, PENNSYLVANIA, ASSIGNOR TO
THE UNION PAPER BAG MACHINE COMPANY, OF SAME PLACE.

METHOD OF AND APPARATUS FOR MAKING PAPER BAGS.

SPECIFICATION forming part of Letters Patent No. 508,059, dated November 7, 1893.

Application filed April 17, 1893. Serial No. 470,622. (No model.)

To all whom it may concern:

Be it known that I, CHARLES B. STILWELL, of the city and county of Philadelphia, State of Pennsylvania, have invented a certain new and useful Method of and Apparatus for Making Paper Bags, of which the following is a true and exact description, reference being had to the accompanying drawings, which form a part hereof.

10 My invention relates to that stage of the manufacture of paper bags in which what is technically known as a diamond folded blank is formed into a bag by the folding of the two flaps of the diamond toward each other.

15 My present invention is applicable to all bags having diamond folds, but is particularly adapted for the completion of what are known as bellows-folded satchel-bottom bags.

The nature of my improved process and apparatus will be best understood as described in connection with the drawings in which they are illustrated and in which—

Figure 1 is an elevation partly in section of my improved apparatus; Fig. 2 an elevation showing the shafts and train of gear forming part of the apparatus; Fig. 3 a plan view of the mechanism shown in Fig. 1 omitting the two feed wheels indicated at C and C'. Fig. 4 is an elevation of a cam forming part of my apparatus; Fig. 5 a perspective view showing the detail of another part of the apparatus; Figs. 6, 7 and 8 diagrams illustrating the operation of the machine upon a paper blank; Figs. 9, 10, 11 and 12 illustrating the blank in various stages of the operation of completing the bag; and Fig. 13 is a perspective view of a completed bag.

To explain first the method of operating upon the blank, Fig. 9 is a perspective view 40 showing a bellows-folded blank with the diamond fold formed upon one end of it. This blank is made by any convenient process or mechanism and is the thing upon which my new operations are performed.

45 A indicates the body of the diamond-folded blank; A' the diamond fold as a whole.

A^2 and A^3 are, respectively, the rear and front flaps of the diamond fold, $a\ a$ and $a'\ a'$ indicating the corners and also the lines upon which the flaps are folded toward each other. In Fig. 10 the front flap A^3 of the diamond is

shown as partly folded upward and backward on the line $a' a'$. In Figs. 11 and 12 this backward folding of the front flap is illustrated as still further progressed, and in Fig. 13 it is shown as completely folded backward and downward upon the center of the diamond. This folding of the front flap may be performed in any convenient way or by any convenient mechanism. In itself it presents no new feature and my new process relates to the folding upward and forward of the rear flap A^2 of the diamond, and this I accomplish by forming a **U**-like fold A^4 in the body of the blank below the rear flap and pushing this **U**-fold upward and forward over the center of the diamond and around a line approximately coinciding with the line $a a$; the rear flap A^2 is pushed upward and forward with **U**-fold and finally pressed down upon the center of the diamond as indicated in Fig. 12—Fig. 11 illustrating the operation as about one-half completed. Preferably the rear flap A^2 is pressed down upon the center of the diamond in advance of the front flap A^3 which is then pressed over it as indicated in Figs. 12 and 13. It will be seen that no permanent crease is formed in the body of the blank by forming the **U**-like fold therein as described, and after the bottom of the bag is closed the **U**-fold can be straightened out leaving no permanent mark upon the blank.

Referring next to the mechanism which I have devised and which I prefer to use in carrying out the above described process or 85 method, B indicates the frame of the machine.

C and C' are feed rolls supported on shafts c and c' the function of which is to engage the blanks delivered to them by mechanism 90 (not shown) for forming the diamond folds. D indicates a guide preferably made adjustable and secured by a binding screw d to a standard projecting from the frame; the function of this guide being to carry the blank 95 from the bite of the rolls C C' to the bite of the rolls C and E which are also feed rolls moving with the same peripheral speed. In front of the rolls C E is a table F over which the bag blank is projected by said rolls. 100

G is a finger secured on the end of an arm G', which in turn is secured to a lever G² piv-

oted at G^3 and having a cam roller G^4 which rests against a double cam H , (see Figs. 3 and 4,) said cam being secured on the shaft c . The action of this cam is to alternately raise 5 and lower the finger G , which, in its lower position, extends through an opening F' in the table F and lies directly in the path of an advancing blank. The action of the finger in this position is illustrated in Fig. 6,—the 10 front flap A^3 of the diamond being pushed upward by said finger as the blank advances from the rolls C and D . As the blank continues to advance the finger G is raised by the action of the cam as is shown in Fig. 7; 15 in this position it permits the blank to move under it on the table, but still keeps contact with the flap A^3 which, as the blank moves forward, is pushed backward over the line a^2 by the end of the finger G which prevents the 20 flap from springing forward until it is nearly in the bite of the feed rolls N N' .

I I are fingers acting intermittently to clasp the blank to the table, hold it there for a defined length of time and then release it. The 25 rear edge of the fingers I should engage the blank at or slightly in advance of the line a a upon which the rear flap is folded forward. The fingers I and the mechanism for operating them are shown in Figs. 1, 3 and 5. They are 30 fastened to a bar I' , the lower end of which, I^1 , projects below the fingers, and the upper end of which, I^2 , is journaled upon a shaft or bolt I^3 , but is clamped upon the said bolt in such a way as not to turn freely thereon, the 35 turning of the hub being resisted by a certain amount of friction. The bolt I^3 is secured on the end of a pivoted lever I^5 , said lever being pivoted at I^6 , and being provided at I^7 with a pin which extends down into the groove of a 40 cam J , said cam being secured upon the shaft e . There are, as appears in the drawings, two of such cams and two similar devices connected with each finger I . On the frame of the machine I secure upwardly-projecting 45 fingers I^8 I^9 between which the depending end I^4 of the rod I' lies. As the end of the lever I^5 is thrown out, the part I^4 comes in contact with the outward finger I^8 and pushes the rod I' and the attached finger I upward. By reason 50 of the frictional resistance by the turning of the hub it retains this position while moving inward and until the end I^4 comes in contact with the inside finger I^9 which moves the bar I' downward and with it the finger I until 55 said finger presses against the table F and clamps the blank between it and the table. This mechanism is arranged as I have already stated so as to engage the blank just in front of the line a a , and the fingers remain in this 60 position clamping and holding the paper motionless upon the table while the finger J is performing its function of throwing forward the rear flap of the diamond, after which the fingers I release the paper and are thrown backward to permit the advance of the blank 65 preferably accomplished by a continued forward motion of the finger J . The finger J

above referred to extends out at right angles to a rod J' , to which it is attached, and which rod is secured at its rear end to a bar J^2 connected in turn to a lever J^3 pivoted at its upper end J^4 to a bracket extending from the frame, and attached at its lower end to a spring L which tends to draw and hold it backward. A cam roller J^5 is secured to the 70 lever J^3 and rests against a cam K , which cam is attached to a shaft k driven from the shaft c' as shown in Fig. 2. From the upper end of the rod J' extends an arm J^6 having at its end a cam roller J^7 which moves in a stationary cam 75 groove M . By this arrangement it will be seen that the longitudinal motion of the finger J is governed by the cam K and its vertical motion by the stationary cam groove M . The 80 action of the two cams upon the finger J and the action of said finger upon the blank is 85 best followed in Figs. 6, 7 and 8. As the blank is fed over the table F the rod J rests beneath it and does not operate upon the blank until it is seized by the fingers I . As soon as it is 90 so seized and its front end held stationary upon the table, the finger J moves upward and forward engaging the blank beneath the rear flap of the diamond fold, and as the blank is fed from between the rollers C and E the rod J takes up the slack and forms the U -shaped fold A^4 in the body of the blank, carrying this fold upward and forward as shown in Fig. 7 and pushing in front of this fold the rear flap A^3 of the diamond fold, 95 this action going on until said rear flap is pushed down upon the central body of the diamond. The fingers I then release their hold upon the blank which is carried forward, preferably by a forward motion of the finger J , until it is engaged by the feed and presser rolls N N' at which time the finger J is rapidly retracted. It will be noticed by reference to the diagram Fig. 2 that the rolls N N' are driven with much greater speed than the 100 rolls C E , consequently they act to roll out and straighten the U -shaped fold A^4 and the bag is delivered from said rollers N N' to any convenient carrying device as, for instance, a belt running on the roller P . 115

It will of course be obvious to one skilled in the art that to operate my method and apparatus to the best advantage the diamond-folded blank should be subjected to a preliminary creasing operation on the lines a a 120 and a' a' .

Having now described my invention, what I claim as new, and desire to secure by Letters Patent, is—

1. The method of making the final folds in 125 a diamond-folded bag blank which consists in folding the front flap of the diamond back, forming a U -shaped fold as A^4 in the body of the blank beneath the rear flap of the diamond, and pushing said fold together with 130 said rear flap forward as described and so as to cause the two flaps of the diamond to overlap and complete the bag bottom.

2. The combination with mechanism for

- holding a diamond folded bag blank, of constantly acting feeding mechanism moving with constant speed in the rear of said holding mechanism and a folder J arranged to engage the body of the blank beneath the rear flap of the diamond and thrust it upward and forward in a U-shaped fold, all substantially as described and so as to fold the rear flap of the diamond forward on the bag bottom.
10. 3. The combination with mechanism for holding a diamond folded bag blank, of constantly acting feeding mechanism moving with constant speed in the rear of said holding mechanism, a folder J arranged to engage the body of the blank beneath the rear flap of the diamond and thrust it upward and forward in a U shaped fold so as to fold the rear flap of the diamond forward on the bag bottom and feeding mechanism situated in front of the holding mechanism and moving at a greater speed than the rear feeding mechanism.
15. 4. The combination with feed mechanism of a table F over which the bag blank is fed and in which is formed an opening F', a finger G arranged above said opening with a backward inclination, and mechanism for raising said finger above the table and lowering it as described; into opening F' so that said finger will engage with and bend up the front flap of the diamond as the blank advances over the table and then raise, permitting the blank to move between it and the table and at the same time push the flap back over the advancing blank.
20. 5. The combination with feed mechanism of a table F over which the blank is fed, intermittently-acting grippers I I arranged to grip the diamond folded end of the blank to the table in front of the rear flap of said diamond and an intermittently-acting rod J arranged to engage the blank below the rear flap and push it upward and forward in a

U-shaped fold to press the flap forward as described.

6. The combination with feed mechanism of a table F over which the blank is fed, intermittently-acting grippers I I arranged to grip the diamond folded end of the blank to the table in front of the rear flap of said diamond, an intermittently-acting rod J arranged to engage the blank below the rear flap and push it upward and forward in a U-shaped fold to press the flap forward as described, a finger G and mechanism for actuating said finger as described and so that it will engage and push up the front flap of the diamond as the blank is fed to the table and then raise permitting the blank to move under it and pushing back said flap as the blank so moves.

7. The combination of the feed roll C with the co-acting rolls C' and E, guides as D whereby the blank is directed from the bite of the rolls C C' to that of rolls C E, the table F set in front of rolls C E to receive the blank, the fingers I I arranged to grip and release the blank at determined intervals, and the intermittently acting rod J arranged to engage the body of the blank and push it and the rear flap of the diamond over fingers I I.

8. The combination of the feed roll C with the co-acting rolls C' and E, guides as D whereby the blank is directed from the bite of rolls C C' to that of rolls C E, the table F set in front of rolls C E to receive the blank, the fingers I I arranged to grip and release the blank at determined intervals; the intermittently-acting rod J arranged to engage the body of the blank and push it and the rear flap of the diamond over fingers I I; and the finger G arranged to engage the front flap of the diamond and to push it back as described.

CHAS. B. STILWELL.
